ROLL CHANGER

Bruce Clark White, deceased, late of New York, N. Y., by Marie Louise White, executrix, New York, N. Y., assignor to R. Hoe & Co., Inc., New York, N. Y., a corporation of New York; Irving Trust Company, permanent trustee

Original application June 20, 1923, Serial No. 646,592, now Patent No. 1,855,503, dated April 26, 1932. Divided and this application March 23, 1932, Serial No. 600,610. Renewed November 13, 1934

6 Claims. (Cl. 242—64)

This invention relates to certain improvements in mechanisms for feeding webs to printing machines and controlling the feed of the webs from web rolls, and is a division of an application of Bruce Clark White, Serial No. 646,592, filed June 20, 1923, on which Patent No. 1,855,503 was granted on April 26, 1932.

The present invention consists in certain novel arrangements of the roll supporting devices by which a plurality of web rolls may be supported and moved from loading to running position within relatively small confines, and the invention further consists in certain novel arrangements in combinations which will be fully described in connection with the accompanying drawings and such features pointed out in the claims hereunto annexed.

In these drawings,—

Figure 1 is a vertical section of a web roll feeding and changing device adapted for a three roll press, each deck being shown with a running roll and a spare roll in different positions;

Figure 2 is a horizontal section on line 2—2 of Figure 1;

Figure 3 is a horizontal section on line 3—3 of Figure 1;

Figure 4 is a horizontal section on line 4—4 of Figure 5, showing one of the roll holders, and

Figure 5 is a vertical section on line 5—5 of Figure 4.

Referring now to these drawings, there is shown for illustrative purposes a three roll machine embodying three roll changers arranged in superposed relation, but it will be understood that this showing is only illustrative and that these roll changers or one of them may be used in other positions and arrangements.

Generally speaking, the novel features of the present invention consist in the provision of a pair of spaced roll holding heads mounted in bearings without a center shaft, so as to leave a clear space between the heads, these heads being provided with bearings for supporting a spare roll and a running roll. These roll supporting bearings are arranged or positioned in the heads so that the distance from the axis of the heads to the center of the roll bearings is less than the radius of a full roll of paper. That is, the changer is capacitated to support a roll of paper the radius of which is greater than the distance between the

centers of the web roll supports and the axis of the head, so that the periphery of a standard full roll of paper may extend inwardly beyond the axis of the heads, such construction permitting the rotating of the heads and the rolls carried thereby in relatively small confines widthwise of the mechanism.

The specific construction and arrangement of the parts may be somewhat varied. In the machine chosen to illustrate the invention there are shown three roll changers, a bottom changer A, a middle changer B, and a top changer C arranged at the end of a three roll or sextuple press, not shown.

The mechanism is suitably supported, as from a base plate 1, to which are secured upright front and rear frames 2, 3 and a support 4 for the lower spare roll. These frames are or may be tied together by means of outer cross-ties 5, middle cross-ties 6, and inner cross-ties 7, and the outer cross-ties 5 may carry extension brackets 8 for temporarily supporting fresh paper rolls marked 9, and a fresh paper roll 10 may also be placed on the support 4.

Referring to the A changer, a fresh roll, of standard size 11, has been rolled inward sufficiently to be secured in the roll holders, which are marked 12, which are shown in the form of a pair of spaced heads. These heads 12 are journaled upon non-rotatable journals 24 and are held against endwise movement thereon by means of a flange 25 outside the head and a collar plate 26 inside the head, as best shown in Figure 4. These journals 24 are fitted to slide freely endwise in hubs 27 projecting inwardly on each side from the frames 2 and 3, but are prevented from rotating therein by a key 28 which has sliding engagement in a key-way 29 of the bearing, best shown in Figure 2, so that the journals may be moved endwise in the frame hubs by means of a screw 30 to which is attached a hand-wheel 31.

A sprocket-wheel 32 is also secured to the screw 30 and has a sprocket-chain 33 trained about it and also about a sprocket 34 on each end of a shaft 35 located below the heads, as shown in Figures 1 and 2. By this means, the operator in turning either of the hand-wheels 31 will rotate both screws 30 in the same direction in such a manner as to move both journals 24 and consequently both heads and the rolls of paper mounted

therein either to the right or left as may be desired, so as to properly introduce the web into the printing elements of the press. The screws 30 have their bearings in a plate 36, see Figure 4.

5 It will be seen that with this construction each of the heads 12 is mounted in a separate bearing or journal without a cross-shaft between them, so that the periphery of a full paper roll positioned in the heads may extend inwardly beyond 10 the head axis, as shown in Figure 1. This results, as hereinafter referred to, in requiring a much smaller space for rotating the heads, so that the heads and the paper rolls carried thereby may be operated in a very narrow space considered widthwise or horizontally of the roll changer mechanism.

10 The heads 12 are rotatably mounted on their bearings and to effect the rotation of the heads they are provided with heavy spur-gears having 20 external gear teeth which mesh in the toothed pinions 38 keyed on a cross-shaft 39 located to one side of the heads. This cross-shaft has keyed thereto a worm-wheel 40 and the shaft is supported in bearings 41 upon the inner cross-tie 7, 25 before referred to, and the shaft is further supported in a journal 42 of the gear box 43, shown in Figure 4. The worm-wheel 40 engages with a worm 45 formed on a shaft 44, which is driven through a clutch mechanism or in any other suitable manner to effect the rotation of the heads when desired, a detail description of this being omitted as unnecessary for an understanding of the present invention, this drive, however, in the present instance being from a shaft 78 driven 35 from the press.

40 The heads 12, in accordance with the invention, are provided with supports for supporting a spare web roll of paper and a running web roll. These supports may vary in construction but they will be located so that their centers, as shown in Figure 1, are so spaced relatively to the axis of the heads that they will support a roll of paper whose radius is greater than the distance between the centers of the roll supports and the axis of the heads, so that the periphery of a fresh roll of 45 paper may extend inwardly beyond the head axis. In the particular instance illustrated, the roll supports are positioned in the heads diametrically opposite each other and adjacent the periphery of 50 the heads.

45 These supports may be of various characters, but in the particular construction shown they are capacitated to engage an iron pipe or core, marked 13 in dotted lines in Figure 2, on which a web roll 55 of paper may be wound. In the particular construction shown, these supports include taper plugs 14 which may be forced into the ends of the tube 13 by means of screws 15 and hand-wheels 16, which have their bearings in plate 17, see 60 Figures 2 and 4. These plugs, as shown in Figures 2 and 4, are preferably rigidly but rotatably mounted in the reels, all spring and like resilient constructions having been omitted.

65 Suitable roll controlling devices may be employed, such being shown in the form of belts 500, 501 arranged on each side of the roll support for controlling the unwinding of the roll, and pasting and web severing devices for joining a new web to an expiring roll may be used if desired, 70 the pasting mechanism being shown as a roll 130 and the web severing mechanism as a knife 133 in Figure 1.

75 It will be seen that with the arrangement adopted the roll changer mechanism may be operated in a very small compass widthwise or hori-

zontally of the mechanism to move a roll from loading to pasting, running and discharge positions. While the arrangement has been shown in its preferred form, it will be understood that certain changes may be made in regard to its 5 form, details of construction and general arrangement without departing from the invention as defined in the appended claims.

What is claimed is:

1. In a web roll changing device, the combination of a pair of independent rotatable web roll supports spaced apart in separate bearings without a center shaft, web roll holders held at a fixed distance from the axis of the supports for supporting a running web roll and a spare web roll, 15 said roll holders being so located relatively to the axis of the supports that they may support a roll of paper whose radius is greater than the distance between the centers of the roll holders and the axis of the supports, so that the periphery of a full roll of paper may extend inwardly to and beyond the axis of the supports, and means for rotating the supports, and for moving the roll axially.

2. In a web roll changing device, the combination of a pair of independent rotatable web roll supports spaced apart in separate bearings without a center shaft, web roll holders held at a fixed distance from the axis of the supports for supporting a running web roll and a spare web 30 roll, said roll holders being so located relatively to the axis of the supports that they may support a roll of paper whose radius is greater than the distance between the centers of the roll holders and the axis of the supports, so that the periphery of a full roll of paper may extend inwardly to and beyond the axis of the supports, means for effecting a relative sidewise movement of the supports, and means for rotating the supports.

40 3. In a roll changing device, the combination of a pair of rotatable heads spaced apart in separate bearings without a center shaft, web roll holders secured in the heads adjacent the peripheries thereof for supporting a running web roll and a spare web roll, said roll holders being so located relatively to the axis of the heads that the periphery of a full roll will extend to a point beyond said axis, means for effecting a relative sidewise movement of the heads, and means for rotating the heads.

45 4. In a roll changing device, the combination of a pair of rotatable heads spaced apart in separate bearings without a center shaft, web roll holders mounted in rigid bearings in the heads and adjacent the peripheries thereof for supporting a running web roll and a spare web roll, said roll holders being so located relatively to the axis of the heads that the periphery of a full web roll will extend to a point beyond said axis, means for effecting a relatively sidewise movement of the heads, means for moving the roll holders axially of the roll to hold and release the roll, and means for rotating the heads.

5. In a device for supporting a plurality of web rolls from which webs are fed successively to a machine, a pair of roll holding heads rotatable on separate bearings axially aligned and movable axially in unison, and a pair of roll supports for each head adapted to engage the cores 70 of the web rolls; said supports on each head being oppositely disposed and spaced apart a distance less than the diameter of a full web roll and having their axes in a plane substantially common to the axis of the head.

6. In a device for supporting a plurality of web rolls from which webs are fed successively to a machine, a pair of roll holding heads rotatable on separate bearings axially aligned and
5 movable axially in unison, power operated means for rotating the heads, and a pair of roll supports for each head adapted to engage the cores of the web rolls; said supports on each head being oppo-

sitely disposed and spaced apart a distance less than the diameter of a full web roll and having their axes in a plane substantially common to the axis of the head.

MARIE LOUISE WHITE,
Executrix of the Estate of Bruce Clark White,
Deceased.
